UNITED STATES PATENT OFFICE.

PERRY J. SNOWDEN, OF ELWOOD, INDIANA, ASSIGNOR OF ONE-HALF TO
SYLVESTER A. MORGAN, OF INDIANAPOLIS, INDIANA.

FEED-WATER HEATER.

SPECIFICATION forming part of Letters Patent No. 739,355, dated September 22, 1903.

Application filed February 11, 1903. Serial No. 142,841. (No model.)

To all whom it may concern:

Be it known that I, PERRY J. SNOWDEN, a citizen of the United States, residing at Elwood, in the county of Madison and State of Indiana, have invented new and useful Improvements in Feed-Water Heaters, of which the following is a specification.

My invention relates to certain new and useful improvements in furnaces, particularly steam-boiler furnaces; and the same will be hereinafter more fully set forth, and particularly pointed out in the claims.

The object of my invention is, first, to produce an artificial draft whereby the flow of the air through the spaces between the grate-bars and the fire thereon will be accelerated to promote combustion; second, to provide means whereby the gases passing from the fire in the furnace will be thoroughly consumed, and, finally, to provide means whereby the waste heat may be utilized for the purpose of heating the feed-water supplied to the boiler to increase the efficiency of the latter. I attain these objects by means of the arrangement and construction of boiler-furnace illustrated in the accompanying drawings, in which similar characters of reference designate like parts throughout the several views.

Figure 1 is a longitudinal sectional view of a steam-boiler furnace, showing my invention applied thereto and taken through the line A B. (See Figs. 2, 3, and 4.) Fig. 2 is a sectional plan view of the same, taken through the line C D. (See Figs. 1, 3, and 4.) Fig. 3 is a front end elevational view of the boiler-furnace; and Fig. 4 is a sectional end elevational view of same, taken through the line E F. (See Figs. 1 and 2.)

The boiler 1, which may be of any suitable or well-known type of tubular boiler, is mounted in the setting 2 over the furnace 3 in the usual well-known manner. The furnace 3 is provided with the furnace-front 4, having the furnace-doors 5, the ash-pit doors 6, the grates 7, and the ash-pit 8. A closing-wall 9 is situated at the rear of the furnace 3, and the said wall is substituted for the usual bridge-wall and is provided with the exhaust-openings or passage-ways 10, through which the unconsumed gases generated in the

furnace 3 are forced into the rear combustion-chamber 11 of the furnace by the steam-jet nozzles 12, thence up the back uptake 13, through the boiler-tubes 14, into the front uptake 15. A steam-jet nozzle 12 is situated opposite each of the passages or exhaust-ways 10, and all have their jet ends directed toward the centers of the opposing passages 10, and said steam-jet nozzles 12 are connected to their connecting-pipe 16, which latter is connected to the steam-supply pipe 17. The steam-supply pipe 17 is connected to either the main steam-pipe 18 of the boiler 1 or it may be connected to some portion of the top of the boiler 1, where dry steam may be obtained. The connecting-pipe 16, being situated within the furnace 3 and subjected to the intense heat generated therein, must be protected. For this purpose I provide the inner tube or pipe 19, preferably of cast-iron, wherein said pipe 16 is inclosed, and said tube 19 has its ends open for the admission of air and is also provided with the nozzle-openings 20, through which the said nozzles 12 project, and the air admitted into the ends of said pipe or casing is discharged through said openings to mix with the gases passing from the furnace 3 through the passage or exhaust ways 10. A tubular shield 21, of fire-clay or other refractory material, surrounds said tube or casing 19 to protect the same from the action of the heat generated in the furnace 3.

In the ordinary steam-boiler furnace the unconsumed gases and smoke pass immediately from the forward or front uptake into a breeching connected to a smoke-stack or directly into a stack, and a quantity of heat is carried away with the escaping gases without being utilized. In order that the heat in said waste gases may be utilized, I construct the top side walls 23 and 24 to extend longitudinally of the boiler-setting 2 the entire length of the boiler 1, and the dividing-wall 25 is situated intermediate the outer walls 23 and 24 and extends from the front of the boiler 1 backwardly to within a short distance of the end thereof, thereby forming a return passage-way 26 and connecting the ends of the parallel flueways 27 and 28. The top portions of said flueways 27 and 28 are closed by

their arches 29 and 30, which extend the entire length of said ways, and said ways are closed at their front ends by the front breeching or casing 31, which connects with the 5 smoke-stack in the usual manner, and said flueways 27 and 28 are separated at their front ends by the dividing-plate 32. The rear ends of said parallel flues are closed by suitable doors 33 and 34.

10 In each of the flueways 28 and 29 are arranged to extend longitudinally therein the feed-water circulating and heating pipes 35 and 36, and said pipes are of greater diameters than their supply-pipes 37, by which 15 latter the feed-water is supplied to said circulating-pipes for the purpose of reducing the velocity of the flow of the water therethrough and permitting said feed-water to be subjected to the heat of the passing gases a 20 longer time to materially raise the temperature of said feed-water before admitting the same into the boiler. The arrangement and construction of the feed-water pipes 35 and 36 I will now proceed to describe.

25 The water-supply pipe 38 extends from the source of supply, as a force-pump, and is provided with a regulating-valve 39. From the top L end 40 of said feed-water-supply pipe 38 horizontally extend the right and left 30 hand branch pipes 37, which are connected, respectively, to the ends of the feed-water-circulating pipes 35 and 36 by the couplings 41 and 42, and the said circulating-pipes 35 and 36 are connected at their opposite ends 35 to the circulating-pipes 43 and 44, respectively, by the T connections 35^t and 36^t, the connecting-pipes 45 and 46, and the T connections 45^t and 46^t, and said pipes 43 and 44 are connected at their opposite ends to the 40 circulating-pipes 47 and 48 by the T connections 43^t and 44^t, the connecting-pipes 49 and 50, and the T connections 49^t and 50^t, and said pipes 47 and 48 are connected at their opposite ends to the circulating-pipes 51 and 45 52 by the T connections 47^t and 48^t, the connecting-pipes 53 and 54, and the T connections 53^t and 54^t, and said circulating-pipes 51 and 52 are connected at their opposite ends to the circulating-pipes 55 and 56 by the T connections 51^t and 52^t, the connecting-pipes 57 and 58, and the T connections 57^t and 58^t, and the opposite ends of said circulating-pipes 55 and 56 are connected to their circulating and 50 collecting drums 59 and 60 at the bottom or 55 near the bottom ends thereof, and connected to or near the top ends of said drums 59 and 60 are the return circulating-pipes 61 and 62, which pipes are of the same diameter as the circulating-pipes above described and extend 60 from said drums 59 and 60 along the interiors of the top parallel flues 28 and 29 to the front of the boiler 1 and in positions relatively thereto to be connected to said front of boiler by the connecting-pipes 63 and 64, by which latter the heated feed-water is fed directly into the said boiler, and the said feed-water is thus circulated back and forth in said circu-

lating-pipes till it has attained a high degree of temperature. The usual elbow-fittings might be employed to connect the ends of 70 said circulating-pipes instead of the T-fittings described; but I prefer to employ the latter, which have their rear open ends plugged or closed by the plugs p, for the reason that the removable plugs p of each of the end T-fittings of any of the circulating-pipes may be readily removed, and thus permitting the operator to remove all deposit or obstructions from the interior of said circulating-pipes without trouble. 75

Any suitable mud-cock or blow-out valve 80 65 may be connected to the bottoms of each of the collecting-drums 59 and 60 for the purpose of blowing out said drums to remove deposit therefrom. 85

The practice of my invention I will now proceed to describe: To start the furnace, a light fire is first made on the bars 7 of the furnace 3 and is gradually increased as the steam is generated in the boiler 1, and when the steam 90 in said boiler has attained a pressure sufficient to operate the steam-jet nozzles 12 the full complement of fuel may be added to the fire. The ash-pit doors 6 are now opened, and the steam is turned on to operate the steam-jet nozzles 12, which, being directed toward and situated opposite the openings 10, discharge a continuous jet of steam through said 95 openings to create a vacuum in the furnace 3, and thereby cause an acceleration of the 100 flow of atmospheric air through the spaces between the grate-bars 7 to and through the fire thereon to thoroughly consume the combustible gases generated and escaping from the fuel. The flow of air into and through 105 the nozzle-openings 20 of the protecting-pipe 19, surrounding the connecting-pipe 16, is also accelerated, and the same is thoroughly mixed with the unconsumed combustible gases that are forced through the openings 110 10 into the rear chamber 11 on the opposite side of the dividing or closing wall 9 to be consumed therein. The flame resulting from the combustion of the gases in the chamber 11 and the hot gases now ascend the back uptake 115 13 and pass through the tubes 14, thence into the front uptake or smoke-chamber 15, thence through the flueway 27 to and through the passage 26, and finally through the flueway 28 into the breeching 31 into a stack connected to the latter. 120

The feed-water-circulating tubes are preferably divided into two sections or series, a right-hand section or series and a left-hand section or series, and each of said sections or series of circulating-pipes are connected to separate and independent collecting-drums 59 and 60, as previously described, the object of such arrangement being particularly to divide the flow of the feed-water into two 125 130 circulating systems and lessen the probability of obstruction by deposit and to reduce the velocity of the flow of the feed-water through each of the series of circulating-pipes.

Having thus fully described this my invention, what I claim as new and useful, and desire to cover by Letters Patent of the United States therefor, is—

- 5 1. In a boiler-furnace, the combination with a main furnace, a boiler, a front uptake or smoke-chamber, and a smoke-stack, of return-flueways situated on and inclosing the top of the said boiler, extending longitudinally thereof and connecting said front uptake or smoke-chamber and said smoke-stack and a series of return feed-water tubes situated within and extending longitudinally of said flues.
- 10 2. In a boiler-furnace, the combination with a boiler-furnace, a boiler, a front uptake or smoke-chamber, and a smoke-stack, of return-flueways situated on and inclosing the top of said boiler, extending longitudinally thereof and connecting the front uptake and smoke-stack, a series of return feed-water tubes situated within and extending longitudinally of said flues and removable plugs in the ends of said tubes.
- 15 3. In a boiler-furnace, the combination with a main furnace, a front uptake or smoke-chamber, and a smoke-stack, of return-flueways situated on and inclosing the top of said

boiler extending longitudinally thereof and connecting said front uptake and said smoke-stack, a series of return feed-water tubes situated within and extending longitudinally of said flueways, removable plugs in the ends of said tubes and collecting-drums connected to said feed-water tubes. 30

4. In a boiler-furnace, the combination with a main furnace, a boiler, a front uptake or smoke-chamber and a smoke-stack, of separate parallel return-flueways situated on and inclosing the top of said boiler, extending longitudinally thereof and connecting said front uptake and said smoke-stack, independent series of feed-water tubes situated within each and extending longitudinally of said flues, removable plugs in each of the ends of said tubes and independent collecting-drums connected to each of said independent series of feed-water-circulating tubes. 35 40 45

In testimony whereof I have hereunto set my hand in the presence of two subscribing witnesses. 50
